DESIGN FOR A TROPHY CUP

George C. De Hart, Los Angeles, Calif.

Application October 19, 1935, Serial No. 59,140

Term of patent 3½ years

To all whom it may concern:

Be it known that I, George C. De Hart, a citizen of the United States, residing at 633½ Tularosa Dr., in the city of Los Angeles, in the county of Los Angeles and State of California, have invented a new, original, and ornamental Design for Trophy Cups, of which the following is a specification, reference being had to the accompanying drawing, forming part thereof.

Fig. 1 is a front elevational view of a trophy cup showing my new design;

Fig. 2 is a side elevational view thereof.

I claim:

The ornamental design for a trophy cup, substantially as shown.

GEORGE C. DE HART.
